GEORGES ROESCH, OF LONDON, ENGLAND, ASSIGNOR OF ONE-HALF TO CLEMENT TALBOT LIMITED, OF LADBROKE GROVE, LONDON, ENGLAND.

CONTROL DEVICE FOR CHANGE-SPEED AND REVERSING MECHANISM.

1,302,593.

Specification of Letters Patent.

Patented May 6, 1919.

Application filed January 19, 1918. Serial No. 212,544.

To all whom it may concern:

Be it known that I, GEORGES ROESCH, a citizen of the Swiss Confederation, residing at London, England, have invented certain new and useful Improvements in Control Devices for Change-Speed and Reversing Mechanism, of which the following is a specification.

This invention relates to control-devices for change-speed and reversing mechanism such as is commonly employed in the gearbox of motor-cars and of machine-tools. The type of mechanism to which it relates, is that in which a lever moving in two planes at right angles to each other is utilized to select from a series of change-speed rods any one required, according to the position into which the lever is moved.

According to the present invention, a gear-changing mechanism comprises the combination with an operating-lever carried by a ball-joint and having an operating end which is below the ball-joint and may be in the form of a second ball, of a shaft which 25 lies approximately at right-angles to the operating-lever, is slidably and rotatably mounted, carries at one end a laterally-projecting selecting finger to engage the gear-changing rods and at the other end a laterally-projecting cup which receives the operating end of the lever.

It further comprises the combination with these parts of a laterally-projecting stop on the cup carried by the sliding shaft, which 35 stop is movable toward or away from the shaft and is spring-controlled to normally keep it at the limit of its movement in one direction, a releasing-rod which extends through the operating-lever has an operating handle at the top of the same and operatively engages with its lower end the said finger within the cup for displacing it against its spring-control when so operated, and a stationary arc-shaped locking-piece 45 which co-operates with the stop so that when the latter is in one of its positions it bears against the locking-piece and limits the movement of the shaft in that direction but when operated by the releasing-rod is brought out from alinement with the said locking-piece so that the movement of the shaft is not thus limited.

In combination with the parts already set forth an inclosing casing may be employed 55 for the sliding shaft and the lower end of

the operating lever, the said casing being provided with a stuffing-box at the point where the ball-joint of the lever is situated so that the latter projects therefrom and the mechanism is rendered dust-tight and 60 oil-tight.

In the accompanying drawings which illustrate one way in which this invention may be carried out,

Figure 1 represents a sectional elevation 65 of the lever and gear shaft, in their containing casing;

Fig. 2 is a view of Fig. 1 as seen from the right, and has a portion of the casing broken away to show the cup and stop; 70

Fig. 3 is a similar view to Fig. 1 showing a modified form of construction;

Fig. 4 is a portion of the part of the casing carrying the arc-shaped locking-piece, as seen from the left-side of Fig. 3. 75

Like letters indicate like parts throughout the drawings.

A hollow lever A, constituting the gear changing lever, is enlarged spherically at A¹ and has a ball-ended lower end A². A rod A³ (hereinafter termed the releasing rod), extends through the lever A from end to end, and is movable endwise therein. Upon the upper end of the releasing-rod A³ is secured a knob A⁴ having a sleeve which 85 extends downwardly and encircles the end of the lever A. This knob serves as a handle for the lever A as well as the releasing-rod A³. A spring A⁵ within the knob keeps the releasing-rod A³ at the upper limit of its 90 travel as determined by a stop A⁶ fixed to the lower end of the releasing-rod.

The spherical portion A¹ of the lever A is supported in a bearing B having a hemispherical cavity therein, so pierced at the bottom as to receive the lower arm of the lever A and to allow it freedom of angular movement about the center of the bearing in all directions. A corresponding cap B¹ for the bearing B is united to the latter by a 100 screw-threaded portion.

The bearing B is mounted in and closes the upper limb of an L-shaped casing C of cylindrical cross section which surrounds the lower arm of the lever A. The lateral extension C¹ of the casing C, carries bearings C², C³ in which a hollow shaft D, constituting a gear - changing shaft, is so mounted that it is both rotatable and slidable endwise. To that end of the shaft D nearest to 110

the lever A is secured a radially projecting hollow arm D¹ forming a cup. The ball end A² of the lever A engages the inner walls of the cup D¹, and is a working fit therein, so that the two members constitute a universal joint having also endwise movement.

In a cavity in the inner end of the cup D¹ and below the ball end A² of the lever A, 10 is a finger E, movable radially in relation to the gear-changing shaft D. From the finger E a stop E¹ projects through a slot D² in the cup D¹ in a direction parallel to the axis of the shaft D and beyond the end 15 thereof. The end of the releasing-rod A³ is adapted to engage with the finger E and when depressed to move it, together with its stop E¹, radially toward the center of the shaft D. A spring E² keeps the finger E at the outer limit of its travel. An arc-shaped 20 abutment C⁵ concentric with the shaft D, constituting a locking-piece, is carried on the wall of the casing C¹ and presents a plane face perpendicular to the axis of the shaft D. When the finger E is at the outer 25 limit of its travel the stop E¹ is radially in register with, *i. e.*, abuts upon the plane face of the locking-piece C⁵.

At the end of the shaft D remote from the 30 gear-changing lever A is secured an arm or selecting-finger F, of which the outer end F¹ is adapted to operatively engage either of the gear-changing rods G¹, G², G³. The endwise movement to the left-hand (as viewed 35 in Fig. 1) of the shaft D is limited by contact of the face D³ of the cup D¹ with the face C⁴ of the bearing C². In this position the end F¹ of the selecting finger F engages with the gear-changing rod G¹. In the position 40 shown in Fig. 1, movement of the shaft D in the right-hand direction is prevented by contact of the stop E¹ with the locking-piece C⁵, in which position the selecting finger F engages with the gear-changing rod G². 45 When, owing to the knob A⁴ being pressed down, the stop E¹ is moved radially inward to clear the locking-piece C⁵, the shaft D can be moved endwise still farther to the right-hand until the stop E¹ is in contact 50 with the wall C⁶ of the casing C¹, in which position of the parts the selecting finger F engages the gear-changing rod G³.

The foregoing arrangement is adapted to 55 suit a gear-box having four forward speeds and a reverse, and the operation of the gear is as follows:—

The gear-changing lever A is by reason 60 of its ball-pivoted mounting adapted to swing both in a fore-and-aft direction of the car, and transversely thereto. By means also of its ball and cup-connection to the shaft D it can impart thereto an endwise movement for the purpose of engaging one of the gear-changing rods and a rocking 65 motion to cause the selecting finger and the

gear-changing rod with which it is engaged to move in the requisite direction to obtain the gear desired. The forward gears are connected to the gear-changing rods G¹, G² and either of these can be engaged by moving the shaft D endwise to the left or right respectively, without depressing the finger E with its stop E¹. The reverse gear only is connected to the gear-changing rod G³ and before this can be engaged by the selector 75 finger F, the releasing-rod A³ must be depressed to depress the finger E and bring the stop E¹ clear of the locking-piece C⁵, so that the shaft D can then be slid to the right (as viewed in the figure) until the 80 selector finger F engages the gear-changing rod G³.

By the above-described arrangement, it will be apparent that the reverse gear cannot be engaged until the releasing-rod has 85 been depressed, thus reducing the risk of doing it inadvertently when the car is moving in a forward direction.

In the alternative construction shown in Fig. 3 which is adapted for cars having 90 three or four forward speeds and a reverse in two lateral displacements, two gear-changing rods only G¹, G² are used. Here the rod G² controls both a forward and the reverse gear. To avoid inadvertently engaging the reverse gear when the rod G² is engaged by the selector finger F, an arc-shaped locking-piece C⁷ on the wall C⁶ of the casing C¹ is so formed as to engage 95 with the stop E¹ and prevent the rotation 100 of the shaft D in the direction required to obtain the reverse gear. When the said stop E¹ is depressed by the releasing-rod A³ to move it clear of the locking-piece C⁷, the shaft D can be rotated and the reverse gear 105 engaged.

To exclude dust and wet from the bearing B of the lever A and also from the interior of the casing C, a hemispherical metal shield A⁷ is attached to the lever A, so that it oscillates with it and completely covers the bearing. A felt or other suitable washer A⁸ encircling the bearing cap B¹, co-operates to prevent dust entering under the shield. 110

It will be apparent that owing to the lever 115 constituted by the laterally-projecting cup D¹ being short, the pressure exerted on it when the cup is operated to move the shaft endwise has little tendency to bend the shaft D. As a consequence the shaft slides freely, 120 and without jamming in its bearings and this freedom is further insured by the fact that the working parts of the mechanism are contained in a dust-proof and oil-retaining casing. In application the mechanism can be 125 situated on the side of a car, where it is most convenient for operation.

What I claim as my invention and desire to secure by Letters Patent is:—

1. In gear-changing mechanism of the 130

- type described, the combination with a rotatable and longitudinally slideable shaft, and a laterally projecting selecting finger fast thereon for actuating the gear changing rods, of an arm fixed on the same shaft, a single operating lever pivotally mounted to rock in two planes at right-angles to one another about a point located intermediate of the ends of the lever and having one end 5 operatively connected to said arm, an abutment fixed relatively to the shaft, a stop mounted movably on said arm and adapted to bear against said abutment in one position of the operating lever and thereby prevent 10 the latter from being rocked in one direction out of that position, and means mounted on the operating lever for moving said stop to clear said abutment, substantially as described.
- 20 2. In gear changing mechanism of the type described, the combination with a rotatable and longitudinally slideable shaft, and a laterally projecting selecting finger fast thereon for actuating the gear changing rods, of an arm fixed on the same shaft, a single operating lever pivotally mounted to rock in two planes at right angles to one another about a point located intermediate of the ends of the lever and having one end 25 operatively connected to said arm, an abutment fixed relatively to the shaft, a stop mounted on said arm to move toward and from the shaft and adapted to bear in one end position against said abutment 30 in one position of the operating lever and thereby prevent the latter from being rocked in one direction out of that position and also prevent the shaft from being slid longitudinally toward said abutment, and means mounted on the operating lever for moving said stop to clear said abutment and thereby permit the shaft to be moved by the operating lever toward the same, substantially as described.
- 45 3. In gear changing mechanism of the type described, the combination with a rotatable and longitudinally slideable shaft, and a laterally projecting selecting finger fast thereon for actuating the gear changing rods, of an arm fixed on the same shaft, a single operating lever pivotally mounted to rock in two planes at right angles to one another about a point located intermediate 50 of the ends of the lever and having one end 55 operatively connected to said arm, an abutment fixed relatively to the shaft, a stop mounted on said arm to move toward and from the shaft and adapted to bear in one end position against said abutment in one 60 position of the operating lever and thereby prevent the latter from being rocked in one direction out of that position, and means mounted on the operating lever for moving said stop to clear said abutment, substantially as described.
- direction out of that position and also prevent the shaft from being slid longitudinally toward said abutment, and means mounted on the operating lever for moving 65 said stop to clear said abutment and thereby permit the shaft to be moved by the operating lever toward the same, said abutment being arranged to prevent rotation of the shaft in one direction in relation to the abutment whenever said shaft is out of said end position, substantially as described.
- 70 4. In gear changing mechanism of the type described, the combination of a casing having a curved abutment at one end thereof, a selecting shaft mounted to slide longitudinally to rotate in the casing, a hollow arm fast on the shaft in proximity to said abutment, a hollow operating lever pivotally mounted in the casing and having one 75 end located in said arm and its other end located outside the casing, a spring-pressed stop movable in said arm toward and away from the shaft and adapted to bear in its end position away from the shaft against 80 said abutment in one position of the operating lever, and a releasing rod extending through the operating lever and having its outer end constituting a handle and its inner end bearing in said arm against said stop, 85 substantially as described.
- 90 5. In gear change mechanism of the type described, the combination with a casing, of a rotatable and longitudinally slideable shaft mounted in the casing, a laterally projecting selecting finger fast thereon for actuating the gear changing rods, an arm fixed on the shaft, a single operating lever pivotally mounted to rock in two planes at right angles to each other about a point 95 located intermediate the ends of the lever and having one end operatively connected to said arm, a stuffing box comprising a hemispherical bearing mounted on said casing forming the bearing for said lever, an 100 abutment fixed relatively to the shaft, a stop mounted movably on said arm and adapted to bear against said abutment in one position of the operating lever and thereby prevent the latter from being rocked in one direction out of that position, and means mounted on the operating lever for moving said stop to clear said abutment, substantially as described.
- 105 110 115 In testimony whereof I have signed my name to this specification in the presence of two subscribing witnesses.

GEORGES ROESCH.
